OSCAR SIMMEN, OF ERLACH, SWITZERLAND, ASSIGNOR TO FIRM SULZER FRERES SOCIETE ANONYME, OF WINTERTHUR, SWITZERLAND

COOLING OF INTERNAL COMBUSTION ENGINES FOR VEHICLES

Application filed July 8, 1930, Serial No. 466,493, and in Germany July 8, 1929.

This invention relates to the cooling of internal combustion engines for vehicles of the kind in which the cooling medium is circulated by one or more electrically driven pumps, the current for the pump motor being supplied either by a generator driven by the main engine or by its exciting machine. The object of the invention is to provide an arrangement particularly suitable for rail vehicles so as to ensure the proper circulation and cooling of the water or other cooling medium even when the power-generating unit is not working, as for example when the vehicle is stationary or is descending an incline. According to this invention an electric storage battery is included in the circuit of the circulating pump motor which enables the cooling medium to be circulated and consequently re-cooled even when the power-generating unit is not working.

In addition to the pump above described a further pump, which is dependent upon the working of the engine, may be provided and the cooling system of the internal combustion engine can if desired be disconnected from the radiators or heat exchange devices by the provision of suitable valves and cocks.

Two arrangements of cooling installation according to this invention are diagrammatically illustrated by way of example in the accompanying drawings as applied to a rail vehicle.

The locomotive 1 illustrated is driven by means of a six-cylinder internal combustion engine 2 coupled to an electric generator 3 from which the current is supplied in the well known way (not shown) to the driving wheels of the locomotive. Instead of a single engine several separate engines may, of course, be employed. In addition to the power-generating unit 2, 3, there is provided a further source of power in the form of a battery 4 which is included in the electric circuit 23 between the generator 3 or its exciting machine 6 and the pump 5 by which

the cooling water is circulated. A charging relay 24 is provided between the generator and the battery so that when the main engine is not working the discharge from the battery through the generator or its excitation machine is prevented.

The pump 5 is connected by the pipe 7 to the cooling jackets 8 of the engine cylinders and also by a pipe 9 to a storage tank 10. The heat exchange devices through which the cooling medium circulates comprise two radiators or heat exchange devices 11 and 12 which are connected by pipes 13 and 14 to the tank 10 and also by a common pipe 15 both to the flow and return pipes 16 and 7 respectively of the cylinder water jackets 8. The direction in which the cooling medium circulates can be reversed by means of three-way cocks 17, 18 or by other appropriate means, the tank 10 being provided with an air vent 19.

In the construction shown in Figure 2 in addition to the pump 5 which can be worked independently of the power-generating plant by means of its battery, there is provided a further pump 20 directly supplied with current from the generator 3 or its excitation machine, this pump being connected to the tank 10 by the pipe 22 and also to the pipe 7. If desired this additional pump may be mechanically driven by the internal combustion engine.

In principle the cooling or heat exchange devices do not differ from those illustrated in Figure 1, and consequently in the drawings similar parts are indicated by the use of the same reference numerals. In Figure 2 however between the pumps 5 and 20 a cock 21 is provided preferably so arranged that the circulation of the cooling medium can be effected either by the pump 5 alone, by means of the pump 20 alone or by both pumps simultaneously.

The installation works as follows:—

The cooling water or other medium in the

tank 10 is drawn by the pump 5 through the pipe 9 (assuming the stop-cock 18 is in the position shown in Figure 1) and delivered through the pipe 7 into the cooling jackets 5 of the cylinders 8 whence it flows through the pipes 16 and 15 into the radiators or heat exchange devices 11 and 12. After being cooled in the heat exchange devices the cooling medium is returned by the tank 10 through the pipes 13 or 14. If desired the circulation of the cooling medium in the jackets of the cylinders can be prevented by turning the three-way cock 18 a quarter turn to the left. Further, by adjusting the three-way cock 17 either the heat exchange device 11 or its companion 12 can be cut out of the circulating system.

When the internal combustion engine 2 is working the pump 5 can be operated (owing to an automatic movement of the charging relay 24) by means of the current supplied by the generator 3 or its excitation machine instead of drawing this current from the battery. In the same way the cooling medium 20 can be circulated by means of the pump 20 if desired either independently of the pump 5 or simultaneously therewith. If the pump 20 is used alone the pump 5 is first cut out of the water circuit by means of the stop-cock 21 so that the pump 20 draws cooling medium through the pipe 22 and delivers it into the pipe 7 whence it circulates through the pipes normally used when the pump 5 is in operation. If desired both the pumps 35 5 and 20 may simultaneously deliver into the pipe 7.

A material reduction in the cooling area of the heat exchange devices is made possible by driving the pump independently of the 40 main propelling engine. If it is assumed that the vehicle driven by the internal combustion engine has to cover a distance from A to B in a time of, say, ten minutes, and that the normal cooling water temperature 45 at the point A is 50° C., whereas in B the generally admissible maximum temperature is 70° C., then if the engine develops 300 engine horse power and 650 heat units per second are carried away per horse power it will 50 be necessary to discharge $300 \times 650 = 195000$ heat units per hour on the section of the journey between A—B, i. e. about 31000 heat units in ten minutes.

If from A to B there is a down gradient 55 enabling the engine to be cut out over the whole or part of the distance, then in the case of a pump driven by the engine the area of the radiator or like cooling device must be so dimensioned that the water can be 60 properly cooled down to the normal temperature of 50° C. solely by virtue of the cooling area available during the ascent to B. To discharge the 31000 heat units required in the above example it will be necessary to have a very large cooling surface which

necessarily increases the size of the cooler and the dead weight of the vehicle.

If, however, the cooling medium is circulated in accordance with the present invention by means of a pump which can be driven independently of the main engine while the latter is stationary, then even though the engine is shut off as when travelling downhill heat can be discharged. Part of the heat to be discharged can be stored up during the climb, as in climbing it is necessary to discharge not 31000 heat units but say only about a half or 16000 heat units. The rest can then be stored and discharged when the engine is stationary or travelling downhill and the cooling devices or radiators can therefore be so dimensioned that in a normal case it is advisable to discharge during climbing only one half the number of thermal units, that is to say only about 16000 thermal units instead of 31000 heat units, so that the radiators or like cooling devices can be of considerably smaller dimensions whilst permitting the temperature of the cooling medium to be adjusted within wide limits to suit the requirements and working.

I claim:

1. In an automotive vehicle, an internal combustion engine, an electric generator driven thereby, a cooling system for the engine, a cooling fluid pump in said system, an electric motor for driving said pump, connections between the generator terminals and the motor, an independent source of current interposed between the generator and the motor, and means in said circuit for automatically alternately connecting the generator and the said independent source to said motor, whereby the cooling fluid may be circulated when the generator is inoperative and vice versa.

2. In an automotive vehicle, an internal combustion engine, an electric generator driven thereby, a cooling system for the engine, a cooling fluid pump in said system, an electric motor for driving said pump, connections between the generator terminals and the motor, an independent source of direct current interposed between the generator and the motor, and means in said circuit for automatically alternately connecting the generator and the said independent source to said motor, and another motor energized solely from the generator and dependent for its operation on the operation of said generator, said motor driving a pump connected to the cooling fluid.

3. In an automotive vehicle, an internal combustion engine, an electric generator driven thereby, a cooling system for the engine, a cooling fluid pump in said system, an electric motor for driving said pump, connections between the generator terminals and the motor, an independent source of direct current interposed between the generator and

the motor, and means in said circuit for automatically alternately connecting the generator and the said independent source to said motor, heat exchangers in circuit with said pump and said engine, and means for disconnecting said heat exchangers from said circuit.

5 In testimony whereof I have affixed my signature.
